Primary Examiner — Prabhakar Deshmukh*(74) Attorney, Agent, or Firm* — Kirk A. Buhler; Buhler & Associates(57) **CLAIM**

The ornamental design for a skin cover for a gaming console, as shown and described.

DESCRIPTION

FIG. 1 is an exploded front elevation view of a skin cover for a gaming console showing my new design;

FIG. 2 is a right side elevation thereof;

FIG. 3 is a top and left perspective view thereof, in an assembled use condition; and,

FIG. 4 is a top and right perspective view thereof, in an assembled use condition.

The broken lines illustrate environment and forms no part of the claimed design.
